UNITED STATES PATENT OFFICE.

FRANK W. BROCK, OF CHATHAM, ILLINOIS.

ADVERTISING DEVICE.

1,027,811.

Specification of Letters Patent.

Patented May 28, 1912.

Application filed January 29, 1912. Serial No. 673,982.

To all whom it may concern:

Be it known that I, FRANK W. BROCK, residing at Chatham, in the county of Sangamon and State of Illinois, have invented a new and Improved Advertising Device, of which the following is a specification.

This invention, in its general nature, comprehends improvements in that class of advertising devices or means that are coöperatively connected with cash registers, sales counters and the like and which are set into operative action when said registers or other change making or counter mounted indicator or registering appliances are operated, and the said invention, in its more specific nature is in the nature of an advertising device or means more especially designed for coöperating with and to be actuated by a money drawer when the same is pulled out in the act of making change, such for example as the money drawer for the ticket selling window of railway stations or other public places.

This invention embodies an endless carrier having advertising signs, cards or other indicator portions so mounted that the said signs or cards are intermittently, under a step-by-step movement of the carrier, brought into view on the counter over which the ticket or money change is passed to the buyer and in which certain automatically set devices are used and are controlled by the outpull and the return movements of the ticket or money drawer for shifting and holding the said endless sign carrier.

In its more specific nature, my invention consists in certain details of construction and peculiar combination of parts, all of which will be hereinafter fully explained, pointed out in the appended claims and illustrated in the accompanying drawing, in which:

Figure 1, is a perspective view, parts being in cross section of a ticket window counter and front with my invention applied, the parts being in their normal position. Fig. 2, is a cross section of the counter, parts being shown in their normal position. Fig. 3, is a similar view, the drawer being pulled all the way out and the parts being shifted for changing ads. Fig. 4, is a top plan view of the operating mechanism, the counter top being removed. Fig. 5, is a detail view showing the fastening of the ad. carrying cloth to the sprocket chains. Fig.

6, is a detail cross section taken on the line 6—6 on Fig. 4.

In the drawings, I have shown my invention as applied for use in connection with the money or ticket drawer of a railway ticket selling counter, but I desire it understood that my said invention may be readily adapted to store counters, bar counters and such other places, where it is customary to hand out goods or money over a table or counter to the buyer.

In carrying out my invention, I employ an endless carrier, holding advertisements, that is intermittently fed forwardly, step-by-step, as the money or ticket drawer is pulled open and in the showing made in the drawings the said carrier consists of two sprocket chains 1—1 of suitable length, for example, one hundred and twenty links and each of the said chains passes over driver sprocket wheels 3—3, and over an upper and lower guide sprocket wheel designated 2 and 20 respectively. The two driver sprocket wheels 3—3 are fixedly mounted on a shaft 4 suitably journaled in the casing sides 5—5 pendent from the under side of the counter 6, and near the rear or inner end of the drawer 7 when the latter is in its closed in position.

8 designates a pinion having say—eleven sprocket teeth loosely mounted on the shaft 4 and it carries a spring pressed pawl 80 that engages a ratchet disk 9 fixedly held on the shaft 4.

10 designates a rack bar that rides on roller bearings 11—12 that engage the upper and lower edges thereof, and the latter is positioned to mesh with the upper edge of the pinion 8 and by reason thereof, when the bar is pulled in the direction of the arrow α , see Fig. 2, the shaft, through the medium of pawl and ratchet devices, before mentioned, is rotated a predetermined degree and thereby moves the chains 1—1 and shifts the advertising cloth 12^a thereon to bring a new advertisement into view of the ticket purchaser, and also a new ad. in the opening 13 in the front of the counter when my invention is applied as shown in Figs. 1 and 2, it being understood that when the rack 10 is returned, by the closing of the drawer, the pinion 8 turns loosely on the shaft 4. To provide for a positive action of the rack and pinion devices, I arrange the drawer 7 in such a manner relatively to the

100

105

110

said rack, and pinion and the inner edge of the counter that the drawer must be pulled out a certain distance before the ticket agent can put money into it or take out any of the 5 contents thereof and in the drawing I have shown the several parts so coöperatively combined that the drawer must be pulled out, say four inches, before easy access thereto can be had, and it is this movement of the 10 drawer that is utilized for actuating the rack 10. For effecting the operation stated and for automatically releasing the rack from the drawer, after it has made the desired pull on the rack 8, I employ a hook 15 member 16, that is pivotally mounted on the rear or inner end of the rack. The hook member 16 is in the nature of a bell crank lever the upper or horizontal member of which terminates in a beveled nose 16^a and 20 has a lock notch 16^b. The member 16 is normally held to its upright position by a coiled spring 17 around the pivot 16^c one end of which is made fast to the rack bar 10 and the other to the member 16. The 25 pendent portion of the member 16 forms a heel for striking a stop 18, located at the rear wall of the counter casing, and the said stop is so positioned that when the drawer has moved out and pulled the rack 10 with 30 it the predetermined distance, the locking hook is swung to release the lock notch 16^b from the hook 19 that projects from the rear end of the drawer.

For holding the rack, the pinion and the 35 ad. carrier to its set position while the drawer remains pulled out and is released from the rack 8, I provide a pivoted lever 21 that includes an upwardly extended member having an inturned finger 22 that rides 40 on the upper edge of the rack 10 and is pulled down into a notch 81 in the said edge by the action of the spring 23, when the rack is pulled out. The lever 21 also includes a heel 24 for engaging a beveled lug 45 25 on the side of the drawer which, when the drawer is shoved in, rides over the heel 24 and tilts the lever 21 to swing its finger 22 out of the notch 81.

From the foregoing taken in connection 50 with the drawings the complete manner in which my invention operates and its advantages will be readily apparent. By reason of arranging the parts, as shown, when a ticket or other sale is made, and the 55 drawer is pulled open, the first "out movement" of the drawer pulls the rack, turns the pinion and through the ratchet and pawl turns the sprocket wheels and shifts the endless sign holding carrier to the next position. During the first movement of the 60 drawer, as stated, the pivoted lever 21 is released to allow its finger 22 to drop into the notch 81 when the rack has been shifted. On the end of the first movement of the 65 drawer, the bell crank lever strikes the stop

18 and releases the rack from the drawer, it being clear from the drawing when the drawer is pushed back, the hook on the rear end rides onto the nose of the lever 16 and the notch 16^b of which, under the coil spring 70 action is moved into engagement with the said hook.

What I claim is:—

1. In an advertising device, a support having at least one sight opening, an advertising carrier, a driving shaft therefor, a reciprocating rack bar, a pinion on said driving shaft coöperating with said rack bar, ratchet and pawl connections coöperating with the said driving shaft to effect a 75 uni-directional movement in said carrier, a drawer member, coöperative connections between said drawer member and said rack bar for reciprocating said rack bar, said connections including a latch member for joining said drawer member to said rack bar, and means for tripping said latch member to release said connection after said drawer member has been moved a definite distance. 90

2. In an advertising device, a support having a sight opening, an advertising carrier mounted on said support and including a driving sprocket, a drawer member mounted on said support, a reciprocating device 95 for operating said driving sprocket and releasable connections between said reciprocating device and said drawer member by virtue of which said drawer member will operate said reciprocating device during a 100 portion of the movement of said drawer member, and means for locking the driving sprocket and the carrier in their shifted position as the drawer completes its movement. 105

3. In an advertising device, a support having a sight opening, an advertising carrier mounted on said support and including a driving sprocket, a drawer member mounted on said support, a reciprocating device 110 for operating said driving sprocket and releasable connections between said reciprocating device and said drawer member by virtue of which said drawer member will operate said reciprocating device during a 115 portion of the movement of said drawer member, means for locking the driving sprocket and the carrier in their shifted position as the drawer completes its movement, the said means being releasable by the 120 return movement of the said drawer.

4. In an advertising device, a support having a sight opening, an advertising carrier mounted on said support and including a driving sprocket, a drawer member mounted on said support, a reciprocating device 125 for operating said driving sprocket and releasable connections between said reciprocating device and said drawer member by virtue of which said drawer member will 130

operate said reciprocating device during a portion of the movement of said drawer member, means for locking the driving sprocket and the carrier in their shifted position, as the drawer completes its movement, and said means comprising a spring-moved lever having a member that interlocks with the reciprocating bar when the same has been moved by the drawer mem-

ber and devices on the said drawer member 10 for releasing the said lever from the reciprocating bar during a return movement of the drawer.
